UNITED STATES PATENT OFFICE.

JEAN GARRET, OF PITTSBURGH, PENNSYLVANIA.

SAFETY-RAZOR.

1,023,372.

Specification of Letters Patent. Patented Apr. 16, 1912.

Application filed January 31, 1911. Serial No. 605,708.

To all whom it may concern:

Be it known that I, JEAN GARRET, a citizen of the United States, residing at Pittsburgh, in the county of Allegheny and State 5 of Pennsylvania, have invented new and useful Improvements in Safety-Razors, of which the following is a specification.

The present invention provides an implement for removing the growth of hair from 10 the face, which may be operated with safety under all conditions and by the most inexperienced person.

The primary object of the invention is the provision of a safety razor of novel construction which will admit of the blade being accurately positioned and retained in place against accidental movement, the device being light in structure and readily separable for sanitary purposes and to 20 admit of sharpening the blade or replacing a dull blade by a new or a sharp one.

The invention consists of the novel features, details of construction and combination of parts, which hereinafter will be more 25 particularly set forth, illustrated in the accompanying drawings, and pointed out in the appended claims.

Referring to the drawings, forming a part of the specification, Figure 1 is a perspective view of a safety razor embodying the invention, parts being broken away. Fig. 2 30 is a transverse section on the line 2—2 of Fig. 1. Fig. 3 is a plan view of the blank from which the frame is formed. Fig. 4 is 35 a section on the line 4—4 of Fig. 3. Fig. 5 is a detail view of the blank from which the blade holder is formed. Fig. 6 is a detail view in perspective of the blade.

Corresponding and like parts are referred to in the following description, and 40 indicated in all the views of the drawings, by the same reference characters.

The frame comprises a base 1 and a guard 2, the base being of oblong form and the 45 guard 2 being located at one edge thereof and of substantially U-form in cross section and consisting of an edge portion of the plate from which the frame is formed bent into the shape substantially as shown. The 50 outer edge of the guard 2 is scalloped or undulating so as to provide projecting portions to touch the skin and prevent the blade cutting into the same. The spaces between the teeth or projecting portions admit of the

blade bearing upon the skin so as to remove 55 the lather and growth of hair therefrom. The base and guard are formed from a blank having the outline substantially as indicated in Fig. 3, an edge portion of the blank having portions cut therefrom to provide an 60 undulating edge of the guard and an open structure adjacent the guard for the sake of lightness and to admit of water reaching the lather so as to clean the frame after using the implement. Portions are pressed 65 upwardly from the base to form loops or keepers 3. The handle may be detachably connected to the frame and preferably consists of two parts 4 and 5 which are connected by means of a screw joint so that the 70 length of the handle may be reduced when it is required to pack the article in compact form. The handle is detachably connected to the frame, the latter having a shank which is externally threaded to receive the 75 threaded end of the handle.

The blade 6 is of oblong form and adapted to be supported upon the base 1 with an edge portion overhanging the guard 2 and approaching close to the outer edge of the 80 guard. Openings 7 are formed in the blade 6 to receive the loops or keepers 3, said openings being positioned to admit of the blade being placed upon the base 1 with either side up or with either edge overhanging the 85 guard. The blade is sharpened upon both edges, thereby admitting of its reversal upon the base. When the blade is in position upon the base the loops or keepers project a short distance above the same so as to 90 receive tongues 8 of the blade holder, said tongues passing through the loops or keepers and extending over the blade to confine the same.

The holder consists of a plate 9 having 95 tongues 8 at one edge, said plate having a finger piece 10. The finger piece 10 is preferably formed by bending a portion of the plate into a roll. The friction of the plate upon the blade and the friction of the 100 tongues 8 within the keepers 3 is usually sufficient to retain the holder in place. However, for greater safety the blade holder may be provided with a spring clip 11, the latter being formed by folding the plate 105 upon itself substantially in the manner indicated in Figs. 1 and 2. The finger piece 10 is formed by partly cutting a portion of

the plate, as indicated in Fig. 5, and bending the part so cut to provide a roll, which extends in front of the plate in position to be conveniently grasped. When 5 the blade holder is removed from the frame the blade may be lifted from the frame and the parts thoroughly cleansed by passing the same repeatedly through water or holding the same in a running stream.

10 From the foregoing description, taken in connection with the accompanying drawings, the advantages of the construction and of the method of operation will be readily apparent to those skilled in the art to which 15 the invention appertains, and while I have described the principle of operation of the invention, together with the device which I now consider to be the embodiment thereof, I desire to have it understood that the 20 device shown is merely illustrative, and that such changes may be made when desired as are within the scope of the claims appended hereto.

Having thus described the invention what is claimed as new, is:—

1. In a safety razor, the combination of a base, a blade supported upon the base, and a holder comprising a clip for securing the blade upon the base, said clip having a portion partly cut therefrom and bent into a 30 roll which extends from the clip to provide a finger piece.

2. In a safety razor, the combination of a base provided with a keeper, a blade supported upon the base and having an opening 35 for the passage of the keeper, and a holder having a tongue passing through said keeper and further provided with a clip to embrace the blade and base.

In testimony whereof I affix my signature 40 in presence of two witnesses.

JEAN GARRET.
